Des. 240,578
Patented July 20, 1976

240,578

PORTABLE BAR

Marten Gottsegen, 1212 Lake Shore Drive,
Chicago, Ill. 61610

Filed July 29, 1974, Ser. No. 492,773

Term of patent 14 years

Int. Cl. D6—06

U.S. Cl. D6—144

Fig. 1

Fig. 2

Fig. 3

Fig. 4

Fig. 5

Fig. 6

Fig. 7

FIG. 1 is a rear perspective view of a portable bar showing my new design;

FIG. 2 is a front perspective view of a portable bar showing my new design with the cover lid removed;

FIG. 3 is a front elevational view thereof;

FIG. 4 is a top plan view thereof;

FIG. 5 is a rear elevational view thereof;

FIG. 6 is a side elevational view thereof; and

FIG. 7 is the other side elevational view thereof with the cover lid removed.

I claim:

The ornamental design for a portable bar, as shown and described.
